MICHAEL J. CAFIERO, OF BROOKLYN, NEW YORK

INSULATING BUSHING

Application filed August 21, 1928. Serial No. 301,121.

The present invention relates to the insulation and protection of electric wires or cables where they issue from conduits and the like, and the objects of the present invention are 5 to provide an insulating bushing or insulating end fitting for such wires, which will be of strong substantial construction and appearance, which can be readily applied and which will hold the conductor or conductors 10 securely and properly insulated from the end of the conduit, and, in the case of multiple conductors properly separated and in desired arrangement relative to each other.

The drawing accompanying and forming 15 part of this specification illustrates certain practical embodiments of the invention wherein the foregoing and other desirable objects are attained, but it should be understood that the structure may be modified as 20 regards these disclosures without departure from the true spirit and broad scope of the invention.

Fig. 1 is a broken side elevation and part 25 vertical sectional view of the invention as embodied in a simple insulating bushing; Fig. 2 is a similar view of the invention as embodied in a conduit end fitting.

The body or shell of the bushing is shown 30 as a short or shallow metallic collar 3 open at the top to receive and form a partial housing for the insulating portion of the device and as internally screw-threaded in its lower end at 4 to screw into position on the upper threaded end of the conduit 5. This collar 35 is illustrated as of generally cylindrical external form and not much larger than the conduit so as to occupy but small space and be capable of use on conduits which may be set particularly close together. To facilitate 40 the screwing of the collar in position on the conduit, the same is shown as having flutes or pockets 6 in the sides of the same to receive a suitable driving tool.

The upper open end of the collar is indicated 45 as having a smooth cylindrical bore 7 extending down to an inwardly projecting annular flange 8. This annular flange by abutment at its lower side against the end of the conduit serves to position and frictionally 50 lock the shell on the upper end of the

conduit and provides at its upper face a seat for the bushing 9 of insulating material.

The insulating member 9 is constructed in the form of a relatively flat or shallow ring or disc having an external diameter to fit down 55 into the cylindrical bore or shell and in some instances to seal on the shoulder provided by the inwardly extending flange 8.

In the case of what is known in the trade as an "insulating bushing", the insulating member 9 consists of a flat ring of insulating material fitting in the upper open end of the shell and having a single large opening 10 therethrough for the one or several cables or wires 11. This ring is shown as having an outwardly extending annular flange 12 at the upper end of the same, resting upon and overhanging the upper end of the shell, so as to be supported by and to form an insulating guard over the upper end of the shell. This ring of insulating material is suitably anchored in its seat so that it will not be displaced when the wires or cables are pulled out of the conduit as by means of drive pins 13 entered through the sides of the shell into 60 seats provided in the dependent cylindrical skirt or body portion of the ring. 70

The annular flange 8 on which the insulating ring rests can be made quite thin 80 as this flange is turned down into abutment with the end of the conduit and any weight on the insulating ring is thereby transferred to the end of the conduit. Thus the shell and insulating ring can be made quite flat or short so as to take up but little room on the end of the conduit and go into small spaces where there is but little room above and about the end of the conduit. Because further of the small amount of material, both metal and insulation, the device can be produced quite 85 inexpensively. The shell and exposed flange of the insulating ring may be of the same size cylindrical form, presenting a smooth neat appearance and being produced by a simple turning or forming operation. 90

In the case of an end fitting where the wires or cables are brought out to a switch panel, motor or the like, the construction is 95 much the same as described, but, as indicated in Fig. 2, the insulating member is 100

more in the nature of a flat disc having as many holes 10^a therein as there are conductors so as to practically close up the end of the conduit about the conductors issuing therefrom. Also this disc may be made somewhat heavier and thicker and need not have the flange overstanding the end of the shell, being finished off for instance, at the upper edge at 14 on a gradual curve down to substantially the inside diameter of the bore or seat in the shell.

To secure the end fitting disc in place, three equi-distantly spaced set screws 15 may be employed extending inwardly through the upper inner wall of the collar in engagement with an annular groove 16 about the lower skirt portion of the insulating member. These set screws and the groove are relatively so placed that the co-operative effect of the two will be to force the bushing firmly down to its seat in the shell. This feature is illustrated at the left in Fig. 2, where the rounded point of one of these screws is shown as bearing against the inclined or bevelled lower wall of the groove. With this construction, it will be seen that the pressure of the screws against this inclined shoulder will be effective to force the insulating bushing member down into the shell and into firmly seated engagement with the supporting shoulder 8 in Fig. 2, or if the same construction is employed in Fig. 1, to force the insulating member into engagement with the lower shoulder 8 and the flange 12 into engagement with its seat on the end of the shell.

The firm seating of the insulating member provides practically a water-tight joint between this member and the shell and also when the screws are set up firmly the insulating member will be held against rotation in the collar, which is an advantage where it is desired to hold the wires or cables in a predetermined relation, for instance, where they are led off to a switch or other piece of electrical apparatus. The loosening of these screws permits the disc to be turned to position the conductors in any particular desired relation.

Another special feature of the thin flat ring or disc like member is that the cable opening or openings therein is or are set radially inwardly beyond the inner edge of the flange 8, so as to guide and hold the cable or cables away from both the edge of this flange and the more or less sharp upper edge of the conduit.

Instead of being previously shaped, the insulating material may be molded into the collar and thereby permanently locked in its seat. To effect such permanent interlock, the surfaces of the collar against which the insulating material is molded may be left unfinished or in the rough, or if desired, an "undercut" may be formed in the inner wall 65 of the collar, so that the material in being

molded will positively interlock with the collar.

What is claimed is:

1. An insulating bushing or end fitting structure for cable conduits, comprising a substantially cylindrical short shell of but relatively little larger diameter than the conduit to which it is to be applied, said short substantially cylindrical shell being internally screw-threaded in its lower end and having a smooth cylindrical bore in its upper end, with a thin inwardly extending annular flange at the foot of the smooth bore and forming an abutment engaging the upper end of the conduit to which the shell is applied and a thin flat disc-like member of insulating material fitting within the cylindrical bore of the shell and resting upon the annular flange at the foot of said bore, said thin flat insulating member having one or more cable openings therethrough for cables issuing from the conduit and disposed radially inward from the inner edge of the annular flange to thereby position and hold said cable or cables inwardly away from the edge of said flange and from the end edge of the conduit to which the device is applied.

2. An insulating bushing or end fitting structure for cable conduits, comprising a substantially cylindrical short metallic shell of but slightly larger diameter than the conduit to which it is to be applied, said shell being internally screw-threaded in its lower end to directly engage the externally screw-threaded upper end of a conduit and having a thin inwardly projecting annular flange at the upper end of the screw threaded portion of approximately mid length of the collar to form an abutment limiting the screwing of the collar onto the conduit and supported by engagement with the end of the conduit, the upper end of the collar having an open cylindrical portion above the annular flange and of larger diameter than the screw threaded lower end portion of the collar and a body of insulating material seated on said annular flange within said cylindrical upper open end portion of the collar, said body having a cable passage therethrough disposed radially inwardly of the flange and of the upper edge of the conduit to which the collar is applied, said insulating body being fixed against rotation in its seat in the collar.

In testimony whereof I affix my signature.

MICHAEL J. CAFIERO.
